(57) **CLAIM**

The ornamental design for a tape roll holder, as shown and described.

DESCRIPTION

FIG. 1 is a front perspective view of a tape roll holder;

FIG. 2 is a lower perspective view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The right side view is a mirror image of the left side view. The broken line shown in the drawings depict portions of the tape roll holder that form no part of the claimed design.

1 Claim, 7 Drawing Sheets
